UNITED STATES PATENT OFFICE.

HORACE W. PEASLEE, OF MALDEN BRIDGE, NEW YORK.

MACHINE FOR WASHING PAPER-STOCK.

Specification forming part of Letters Patent No. 12,283, dated January 23, 1855; Reissued January 8, 1856, No. 340.

To all whom it may concern:

Be it known that I, HORACE W. PEASLEE, of Malden Bridge, in the county of Columbia and State of New York, have invented 5 certain new and useful Improvements in Machinery for Washing Paper-Stock; and I do hereby declare that the following is a full, clear, and exact description of the same, reference being had to the accompanying drawings, forming part of this specification, in which—

Figure 1, is a view of that end of the machine where the discharge of the washed stock takes place. Fig. 2, is a longitudinal 15 vertical section through the center. Fig. 3, is a transverse vertical section looking toward the entrance to the cylinder. Fig. 4, is a transverse section looking toward the discharge end of the cylinder.

Similar letters of reference indicate corresponding parts in the several figures.

To enable others skilled in the art to make and use my invention, I will proceed to describe its construction and operation.

A, A, is the framing of the machine consisting of two strong standards and longitudinal stretchers. This framing carries the trough, T, in which rotates the washing cylinder, a small portion of the lower part 30 only of which is intended to be immersed in water. The cylinder is made of woven wire-work attached to two strong metal rings C, C, one at each end, which are furnished outside with ways a, a which fit to 35 grooves in rollers D, D, which are secured to shafts E, E, whose journals fit to bearings b, b, on the standards A, A. The rollers D, D, form bearings in which the cylinder is capable of rotating. A portion c of each 40 ring, C, passes through a circular opening in one of the standards A, A, in which it fits very loosely so as not to produce friction, the object of these portions of the ring being to bring the open ends of the cylinder flush with, 45 or beyond the outer faces of the standards, and to keep the ends of the troughs which consist of parts of the standard, almost tightly closed, so that very little, if any, water escapes outside or around the cylinder. Each 50 ring, C, is furnished with spur teeth all round to gear with one of two spur wheels on the driving shaft G, which works in bearings on the standards, above the cylinder, and receives rotary motion from any suitable motive agent, for the purpose of

giving revolution to the cylinder. The cylinder is strengthened by longitudinal wooden strips c, c, which are close to the inner surface of the wire work, and serve to hold the hooks, or bent teeth d, d, which are 60 made of steel with sharp points and are of such bent form that they will catch and carry up the rags or other stock, as they rise with the revolution of the cylinder, and will drop it as they severally rise to their highest 65 positions, as shown at d', d', in Figs. 3 and 4. These hooks are arranged in a spiral line winding several times around the cylinder as shown in Fig. 2, the direction of the spiral being such as will cause the stock to be 70 carried from the end L, of the cylinder where it is fed in, to the other end M, where it is discharged. At the end, L, of the cylinder where the stock is to be fed in there is a chute H, secured to the standard A, and 75 extending a short distance into the cylinder, as shown in Fig. 2. At the opposite end of the interior of the cylinder are the oblique curb pieces, K, K, of which there may be any desired number arranged at equal distances apart and firmly bolted to the cylinder, extending from the inner edge of the part c, of the ring, C, a short distance into the cylinder, and being of such depth as to form a barrier to prevent the too free escape 80 of water through the end of the cylinder. The spaces between the curb pieces form channels, and the direction of the obliquity of the pieces is such that the washed stock which has arrived at that end of the 85 cylinder rolls down the channels on the ascending side of the cylinder, and is thus discharged.

The cylinder is kept constantly supplied with water which is thrown on the stock both as it enters the chute H, and, also, while it is being carried along the cylinder, from a pipe, O, which is furnished with a nozzle, N, which is so directed as to throw a stream directly on the stock as it is entering the cylinder, and which extends all along the ascending side of the cylinder, and is perforated, to throw a number of smaller streams through the whole length of the wire-work of the cylinder, to meet the stock 95 as it is being carried up by the revolution of the cylinder. The pipe, O, should be so supplied as to throw the water upon the stock with great force, to wash out the dirt.

While the machine is in operation the 110

- supply of water is so controlled by cocks in the nozzle N, and perforated jet-pipe, O, and the escape from the trough so controlled by a sliding gate, P, at its bottom, that the 5 cylinder is kept flooded only to about the level of the top edge of the lowest curb piece, K. The stock is fed in continuously by hand down the chute, H, in such quantities as to keep the cylinder about one-third 10 full, or in greater or less quantities as may be found desirable, and as soon as it enters is caught by the hooks, and carried up to meet the jets which enter the ascending side of the cylinder from the pipe, O, after which 15 by its continued ascent it is drained until it reaches the top of the cylinder and drops again into the water at the bottom to be again caught up and submitted again to similar operations which continue to be re- 20 peated until it is carried by reason of the spiral arrangement of the hooks, to the end, M, of the cylinder and in the end is discharged therefrom by being carried up among the oblique curb pieces to such a position that it will slide or roll down upon 25 and between them. The washing operation may be repeated as often as necessary either in the same machine or different machines of the same construction.
- 30 The flooding of the cylinder may be further regulated by a slide at the lower part of the end M, by raising or lowering which the level of the water may be varied, and always kept above the level which would be allowed. The cylinder may revolve at the 35 rate of about 15 or 20 revolutions per minute, but this may be varied as may be found desirable.

Instead of arranging the hooks spirally 40 around the cylinder they may be arranged in rings, but in that case the cylinder will require to be placed at a slight inclination in order that the stock may be carried through by gravitation. The principal ob- 45 ject of the spiral arrangement of the hooks is to avoid placing the cylinder in an inclined position, as when thus placed the water cannot be at the same level throughout but must be deepest at the discharge end 50 where the curbs would require to be so high to prevent the escape of water, that proper facility for the discharge of stock would not be had.

The oblique curbs (K), it will be ob- 55 served, are arranged in continuous and close succession around the discharge end of the cylinder, and the passages between them form, of themselves, channels (without the aid of additional spouts as in certain ore 60 washing machines) to incline or discharge the washed stock beyond the range or travel of the discharge end of the cylinder, so that, the stock, leaving the cylinder, will not be caught up by the end of the cylinder in its 65 rotation and the motion imparted to the

stock by the cylinder's rotation, inclining the stock to be discharged at one side, is neutralized by the oblique run given to the stock in the opposite direction down the channels formed by the curbs, whereby the 70 stock is discharged toward the center of the trough in the water therein and the accumulation of stock in the trough on and against the rising side of the cylinder, by the rub of the cylinder on the light stock, is 75 counteracted. In addition, however, to these offices or actions on the stock, of the oblique curbs (K), they, in being arranged in continuous succession around the open discharge end of the cylinder, in no way interfere with or impede the constant and regular discharge of stock, thereby causing more general and uniform washing of the stock, and a regular or evenly continuous but slow escape or run of water out of the discharge end of the cylinder is insured, the curbs (K) acting as a barrier to the too free escape as described and causing a copious supply of water to be retained in the cylinder for the proper washing of the 80 stock. Thus the uses and duties of the oblique curbs (K), arranged as described in continuous succession around the open discharge end of the cylinder, are important 85 and numerous in the washing of the stock; 90 and in checking the run of the water out of the discharge end of the cylinder, they control or limit the flow or travel of the stock through the cylinder to a speed corresponding and in accordance with the discharging or conveying action of the cylinder itself or of the spiral arrangement specified 95 of the elevating hooks (d), to enable the said hooks to grip the several portions of the stock, elevate the stock to the highest 100 point of the cylinder to drain and constantly subject the stock to such repeated action by the several hooks in succession as described, and whereby the stock is more thoroughly washed and cleansed. Were it not for the 105 check given to the escape by the oblique curbs (K) the stock would be washed too rapidly out of the cylinder for the full and regular action in succession of the elevating hooks (d) and a less copious and insufficient 110 supply of water to effect a thorough washing of the stock would be retained in the reticulated cylinder.

I do not claim as new the revolving screen cylinder and stationary trough, with or 115 without elevating hooks or lifters arranged spirally or otherwise in the cylinder for the purposes specified; nor yet, otherwise than as arranged and combined, the oblique curbs or pieces to direct the discharge from the 120 cylinder, as such devices, differently arranged employed and combined, have before been used in ore washing machines: But

I do claim as new and useful

In the washing of paper stock, the ar- 130

angement, substantially as herein shown and described, of the oblique curbs (K) in continuous succession around the open discharge end of the revolving screen cylinder and forming channels between them to conduct the stock continuously, as the cylinder rotates, beyond the discharge edge of the cylinder; when combined to operate together with elevating hooks (d) within the cylinder, and serving to retain a copious supply of water in the cylinder for the proper washing of the stock and to check the run of the

stock through the cylinder to a speed in accordance with the conveying action of the cylinder or its elevating hooks (d) as specified, to insure the full and regular action of the hooks on the stock in the manner described; the whole operating together as and for the purposes set forth. 15

HORACE W. PEASLEE.
